CLAIM

The ornamental design for a margin setter for use with
a typewriter or printer, as shown and described.

DESCRIPTION

FIG. 1 is a perspective view of a margin setter for use
with a typewriter or printer showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom view thereof.

FIG 1

FIG. 2.

FIG. 6.

FIG. 3.

FIG. 7

FIG. 4.

FIG. 5.
